INVALID UTILITY BED

Frank J. Pirone, Brentwood, and Hans K. Hamann, Bronx, N. Y., assignors to Geriatric Utility Bed Corporation, Mount Vernon, N. Y., a corporation of New York

Application May 31, 1950, Serial No. 165,322

5 Claims. (Cl. 5—60)

1

Our invention relates to improvements in utility beds which are especially adapted for the treatment of geriatric patients in hospitals and like institutions.

We have invented an invalid bed of simple sanitary construction which is equipped to provide for the comfort of patients and facilities for treating and caring for even such invalids as those who are in a helpless condition. Our bed comprises a frame upon which a sheet of canvas or the like can be stretched to support a patient and can be removed readily for laundering and sterilizing. On April 12, 1949, we filed an application for patent as Serial No. 86,944, now abandoned, in which our invention as it had been developed up to that time is described and claimed. This bed has gone into successful use. Since that time we have made the improvements described herein, for which we desire patent protection.

Referring to the drawings:

Fig. 1 is a side elevation and Fig. 2 an end view of a bed which is made according to and embodies the aforesaid improvements.

Fig. 3 is a perspective view of some of the parts shown in the preceding figures drawn on a larger scale. The view in this figure is taken on the line 3—3 of Fig. 1.

Figs. 4 and 5 are similar perspective views of other parts which are shown in Figs. 1 and 2. The views in both of these figures are taken from the line 5—5 of Fig. 1 and show the same parts in different relative positions.

A detail of construction is shown in Fig. 6, this being a plan view taken on the line 6—6 of Fig. 2.

The frame of the bed comprises vertical posts 10, interconnected at their upper ends by longitudinal members 11, 12, and transverse members 13, 14. They are also interconnected intermediate their lengths by longitudinal members 15, 16 and transverse members 17, 18 located above the numbers 15, 16. These parts are preferably of square hollow metallic tubing, welded together as shown, but the longitudinal members 11, 12, 15 and 16 may be detachably connected to the posts. A flat metal transverse bar 19 is welded to the posts which are at the end of the frame, which we will call the head. This bar is located near the lower end of the posts.

20 designates a longitudinal member rotatably mounted in the posts 10, 10 at what we call the front of the bed. It is located above the member 15 in horizontal alinement with the members 17, 18. Channel brackets 21 are welded to the ends of the member 20, in which are rectangular openings 22. 23 designates levers welded to the brack-

ets and projecting at right angles from the member 20. Pintles 24 project from the member 20 through these brackets. The pintles pass through perforations in the posts 10, whereby the member 20 is pivotally supported.

At the side of the member 20 from which the levers 23 project, are a plurality of spaced studs, designated by S.

It is to be understood that a similar longitudinal member is rotatably supported on the posts 10 at the rear of the bed, together with parts like those which are designated by the reference numerals 21—24.

According to our invention, a sheet of canvas or the like, designated by C, having grommets along its edges, is placed over the frame thus described, and is attached thereto by passing the grommets over the studs on the member 20, studs on the bar similar to 20 at the rear of the bed, and similar studs on the transverse members 17, 18. This is done when the levers 23 are in the positions shown at the right-hand side of Fig. 2 and in Fig. 4. A hook 25 pivoted on the outside of a post 10 passes through the opening 22 in the bracket 21 and holds the parts in the positions shown in Fig. 4. Then, when the levers 23 are turned to rotate the member 20 180 degrees, the studs will be moved to the position shown in Figs. 1 and 5, and the canvas will be stretched thereby.

30 A hook 25A pivoted on the inside of the post 10 is used to hold the member 20 with the studs 5 in inverted position (see Fig. 5).

30 designates one of a pair of side brackets, each of which comprises two vertical posts 31, 32, the upper ends of which are connected by a horizontal arm rest 33 and by an obliquely disposed bar 34. The bars 32, 33, 34 are provided with studs S for supporting strips of canvas or the like to form a seat for a patient and a table. Flat strips 35, 36 extend downwardly from the posts 31, 32 to the longitudinal bar 15, to which they are hinged, as shown at 37 in Fig. 3. Both of these strips are offset as shown at 35A in Fig. 3 to clear the longitudinal member 20.

45 The post 32 is spaced longitudinally from the adjacent post 10 of the frame. 38 is an extension projecting from the post 32 to span this space. 39 is a hook pivoted to the extension. When the side bracket is rotated to the position shown in Figs. 1 and 3, the hook is turned into a space formed between the inner side of the adjacent post 10 and a strap 19A to hold the bracket in its raised position. When it is desired to lower the side brackets the hook is moved out of this space and the bracket is rotated about its hinges 37 into

the position under the bed in which it is shown at 30A in Figs. 2 and 6. The hook 39 may then engage the crossbar 19 near one of the notches therein (Fig. 6).

A pair of doors 40 is provided at each end of the bed. These are pivoted in brackets 41 welded to the posts 10. When closed, the adjacent edges of each pair are fastened together by a keylock at 42.

A pair of brackets 43, 44 are welded to each door near its pivoted edge. When the doors are closed the bracket 43 is positioned over the hook 25A to prevent its removal from the bracket 24. The bracket 44 will then be over the hook 39 if the latter is in the space between the post 10 and the strap 19A.

One or more pairs of self-locking rollers 50 are provided on the longitudinal bars 11, 12, between which a strap 51 for lifting a patient may be passed.

Various modifications in construction, mode of operation, method and use of an invention may and do occur to others, especially after benefiting from knowledge of such a disclosure as that herein presented of the principles involved, but the invention itself is not confined to the present showing.

We claim:

1. A bed structure comprising four vertical posts, longitudinal and transverse stationary horizontal members affixed to said posts to form a rectangular frame, a pair of side brackets hingedly supported on the longitudinal members of the frame, end doors hinged to the posts at the ends of the frame, hooks pivoted on the side brackets arranged to engage the posts on which the doors are supported, and projections on the doors positioned to engage said hooks when the doors are closed to maintain the engagement of the hooks with the posts.

2. A bed structure comprising four vertical posts, longitudinal and transverse stationary horizontal members affixed to said posts to form a rectangular frame, a member pivotally supported on two of the posts, a plurality of spaced studs projecting from one side of the pivotally supported member, a bracket projecting radially in one direction from one end of the pivotally supported member, a hook on one of the vertical posts in which the member is pivoted for engaging the bracket when the member is rotated to bring the bracket into a position above the pivotally supported member, a second hook on the same post for engaging the bracket when the member is rotated to bring the bracket into a position below the pivotally supported member, said hooks being pivoted about axes transverse to the pivoted axis of said member and a sheet having grommets affixed thereto near its edges spaced to register with the studs, each grommet receiving a corresponding stud to connect the sheet to the pivotally supported member.

3. A bed structure comprising four vertical posts, longitudinal and transverse stationary horizontal members affixed to said posts to form a rectangular frame, a pair of parallel members pivotally supported on the posts, a plurality of spaced studs projecting from like sides of the pivotally supported members, brackets projecting radially in one direction from like ends of the pivotally supported members, hooks on the vertical posts adjacent said brackets for engaging the brackets when the members are rotated to bring

the brackets into positions above the pivotally supported members, other hooks on the same posts for engaging the brackets when the members are rotated to bring the brackets into positions below the pivotally supported members, said hooks being pivoted about axes transverse to the pivotal axes of said members and a sheet having grommets affixed thereto spaced to register with the studs, each grommet receiving a corresponding stud to connect the sheet to the pivotally supported members.

4. A bed structure comprising four vertical posts, longitudinal and transverse stationary horizontal members affixed to said posts to form a rectangular frame, a pair of parallel members pivotally supported on the posts, a plurality of spaced studs projecting from like sides of the pivotally supported members, brackets projecting radially in one direction from like ends of the pivotally supported members, hooks on the vertical posts adjacent said brackets for engaging the brackets when the members are rotated to bring the brackets into positions above the pivotally supported members, other hooks on the same posts for engaging the brackets when the members are rotated to bring the brackets into positions below the pivotally supported members, end doors pivoted on the posts on which are the hooks and projections on the doors overlying, when the doors are closed, the hooks which engage the brackets being in positions below the pivotally supported members and being pivoted about axes transverse to the pivotal axes of the members.

5. A bed structure comprising four vertical posts, longitudinal and transverse stationary horizontal members affixed to said posts to form a rectangular frame, a pair of parallel members pivotally supported on the posts, a plurality of spaced studs projecting from like sides of the pivotally supported members, brackets projecting radially in one direction from like ends of the pivotally supported members, hooks on the vertical posts adjacent said brackets for engaging the brackets when the members are rotated to bring the brackets into positions above the pivotally supported members, other hooks on the same posts for engaging the brackets when the members are rotated to bring the brackets into positions below the pivotally supported members, said hooks being pivoted about axes transverse to the pivotal axes of said members straps on said vertical posts above the hooks thereon, a pair of side brackets hingedly supported on opposite longitudinal stationary members of the frame, side bracket hooks engaging said straps, end doors pivoted on the posts on which are the hooks and projections on the doors overlying, when the doors are closed, the hooks which engage the brackets in positions below the pivotally supported members and said side bracket hooks.
